UNITED STATES PATENT OFFICE.

JULIUS KRAMER AND DANIEL A. BRENNAN, OF CHICAGO, ILLINOIS, ASSIGNEES TO
PULLMAN COUCH COMPANY, OF CHICAGO, ILLINOIS, A CORPORATION OF ILLINOIS.

CONVERTIBLE FURNITURE.

1,145,248.

Specification of Letters Patent.

Patented July 6, 1915.

Application filed March 26, 1914. Serial No. 827,324.

To all whom it may concern:

Be it known that we, JULIUS KRAMER and DANIEL A. BRENNAN, citizens of the United States of America, and residents of Chicago, in the county of Cook and State of Illinois, have invented certain new and useful Improvements in Convertible Furniture, of which the following is a specification.

This invention relates to convertible furniture of the class in which a series of foldably related bed sections, are arranged to unfold to form a bed and in which the mattress and bedding may be folded in with said sections when the bed bottom is folded, and more particularly to furniture of this character in which a separate top member is removed from its normal position in converting the device into its bed form.

The main objects of this invention are to provide an improved form of convertible furniture which shall be simple in construction and easy to operate; to provide an improved form of mounting for the bed bottom adapted for use in different kinds of furniture, and means for carrying out the folding and unfolding operations; to provide an improved form of top member and automatic means for moving and disposing of the same when the bed bottom is moved in the process of converting the device into its bed form and vice versa; and especially to provide a table bed embodying these features.

An illustrative embodiment of this invention is shown in the accompanying drawings, in which—

Figure 1 is a top plan view of an embodiment of this invention in table-bed form, with the table top turned back and the bed sections unfolded. Fig. 2 is a side view of the device shown in Fig. 1 also in its bed position, and with the rear end of the frame removed. Fig. 3 is a side view of the table bed in its folded or table position, with the near end of the frame removed. Fig. 4 is a side view of an embodiment of the invention in bureau bed form, with the near end of the frame removed. Fig. 5 is a side view of the bed bottom of the device shown in Fig. 4 in its folded form. Fig. 6 is a front elevation of the bureau bed shown in Fig. 4. Fig. 7 is an axial section of one of the rollers and associated parts on the line A—A of Fig. 3, illustrating how the bed bottom is

carried reciprocatably by the frame. Fig. 8 is an axial section of one of the friction clamps and associated parts, on the line B—B of Fig. 3. Fig. 9 is an enlarged perspective view of a bracket for the front panel of the device. Fig. 10 is a broken side view of section 18 and coacting parts of adjoining members, showing a modified form of slot and shoulder means for folding the rear leg.

In the table bed construction shown in Figs. 1, 2 and 3 of the drawings, the device comprises a housing or frame 1 having sides 2 and a back 3 in combination with a foldable bed bottom 4 reciprocatably mounted between and supported by the ends 2, and a movable top 5 preferably hinged at one side as at 6 for turning back when the device is converted into a bed.

The bed bottom 4 comprises three long sections 14, 15 and 16, and two short connecting sections 17 and 18 hinged together in alternate position and adapted to be folded together with the long sections lying substantially horizontal and with the short sections disposed vertically.

The connection of the bed bottom 4 to the table frame 1 comprises coacting means on each side of the bed adapted to facilitate drawing the folded bed bottom forward as a whole and restoring it to its retracted position in the frame. To this end one of the bed sections 15, preferably medial of the bed bottom, serves as a non-turning carrying member whereby the bottom is supported in the table frame, the other sections being foldable with respect thereto and preferably upon its upper side as shown in Fig. 3.

In order that the forward and backward movement of the folded bed bottom may be substantially frictionless the carrying section 15 is provided with roller bearings constructed and arranged preferably as follows: Inwardly facing channel bars 20 are disposed horizontally in and secured to the table frame, one at each side of section 15, said bars being adapted and arranged to serve as guideways or tracks for rollers 21, 22 and 23 journaled upon the sides of the frame 15. The rollers on each side are preferably arranged in sets of three, one adjacent to the front edge and adapted to coast with and rest upon the guide channel when the bed bottom is retracted, and the other two

being spaced apart somewhat adjacent to the rear edge and adapted to support the section 15 in horizontal position independently of other means when the bed bottom is advanced to its bed position. The rollers 5 are preferably journaled upon horizontally projecting lugs or brackets 25 secured rigidly to the side rails of section 15.

When the bottom 4 is folded one of the 10 ends, preferably the head section 14, is disposed between the middle and opposite end sections, said section 14 being somewhat shorter than the other main sections, and the adjacent connecting section 17 being somewhat shorter than the opposite connecting section 18. The said differences in 15 length are adapted to permit folding in with the sections the mattress and usual bedding, not shown.

20 The outwardly disposed or foot section 16 and sections 15 and 18 to a great extent are supported in their bed position by means of foldable legs 29 and 30 pivoted at 31 and 32 to the outer ends of sections 15 and 25 16 respectively. These legs are automatically controlled, preferably by means of links 33 and 34 pivoted to the upper ends of the legs and next rearwardly adjacent short sections 17 and 18 respectively.

30 Section 17 is braced by a rod 35 connected at its ends to medial portions of the side rails, said rod preferably being U-shaped and having pivotal end connections. Section 18 carries a side panel or apron member 36 of the table, which serves to hold the side rails spaced apart, and hides the bed sections when they are folded away. Panel 36 is preferably spaced somewhat from the section 18 so as to provide ample clearance 35 for the bed spring, brackets 36 being interposed between the panel and side rails. Suitable handles or pulls 37 are provided on the panel 36 to facilitate drawing out the bed bottom.

40 45 Connective mechanism is provided for raising and turning back the top 5 simultaneously with advancing the bed bottom in changing the device from table to bed form and vice versa. For this purpose a pair of 50 operative connecting means are provided, as levers 38, pivoted one to each end 2 of the stationary frame, one arm 39 being much longer than the other arm 40, and the fixed pivot 43 being preferably adjacent to and 55 somewhat above the retracted position of the carrying section 15, and the downward arm 40 being inclined forward somewhat from alinement with arm 39. A pair of stops or shoulders 45 and 46 are provided 60 on said section 15 adapted and arranged for coaction with the short arm 40 for oscillating the lever when the bed bottom is reciprocated, the forward stop 45 being a little higher than the rear stop 46. A pair of 65 brackets 48 are disposed transversely upon

and secured to the under side of the table top adjacent to each end, said brackets each being provided with a longitudinal guideway or slot 49 adapted and arranged for receiving and guiding the upper end of the 70 long arm 39. When the bed bottom is drawn forward the rear stop 46 contacts against the rear side of arm 40 and rotates the lever which operates to turn back the top 5 to its vertical position. By this action 75 the arm 40 turns far enough to permit stop 46 to go past the under end of the lever, and section 15 is free to move forward to its bed position. When the bed bottom is pushed back into the frame the forward and upper 80 stop 45 contacts against the lower end and opposite side of arm 40 and restores the lever to its original position, and thereby restores the top 5.

85 The connection or joint 50 between the lever arm 39 and the bracket 48 is formed and adapted to produce sliding friction sufficient to prevent free and accidental slipping of the connection in the slot when the top is raised, but not enough to materially 90 affect the operation of the device in folding and unfolding. The friction joint 50 is preferably adjustable, and in the form shown comprises a bolt or screw 53 in combination with a compression spring 54 protected by a cap 55 and washers 56, said screw being adjustable for securing a proper degree of friction by means of a nut 57 and thumb set nut 58.

95 100 The operation for unfolding the bed is as follows: The bed bottom is drawn forward and the table top is raised simultaneously. This is done preferably by pulling on the handle 37 with one hand and lifting on the table top with the other to assist the lever mechanism. The bed sections are then unfolded to the position shown in Fig. 2, the foot section being unfolded first, and then the head section.

105 110 The folding operation is as follows: First the head section is folded upon the middle section and then the foot section is turned over and down upon the head section. The folded bed bottom is then pushed back into the frame and the table top thereby swung 115 down simultaneously to its normal position, the forward edge of said top preferably being grasped by one hand as it swings forward, whereby it may be lowered gently into place.

120 125 The main features of this invention may be embodied in a bureau bed as illustrated in Figs. 5 and 6, in which case the device comprises a housing or frame 61 having sides 62 and a back 63, in combination with a foldable bed bottom 64 and a top 65 hinged as at 66, all corresponding substantially with the several members 1, 2, 3, 4, 5 and 6 respectively of the table bed above 130 specified. The bureau bed also comprises a

plurality of drawers 68, a mirror 69 and a supporting frame 70 therefor.

In the bureau bed, the legs and folding mechanism are modified somewhat, the legs on each side of the bed preferably both being pivoted to the foot section 16 as illustrated in Fig. 5. The outer leg 74 is pivoted at 75 adjacent to the outer edge of the foot section, and the upwardly projecting end is 10 pivotally connected to a link 76 which at its opposite end is pivoted to section 18 at a point 77 medially disposed thereon. The rearward leg 78 is pivoted to section 16 at 79 adjacent to the rear edge. The upwardly 15 projecting end of the leg 78 is bent forward and provided with a shoulder or pivot 90 thereon and adapted to slide in a longitudinal guide slot 92 formed in the link 76. In folding over the foot section upon the middle section the link 76 operates to retract the outer leg 74 as will be understood, and at the same time the link 76 in moving away from the inner edge of the foot section will cause the shouldered end of the inner leg to travel 25 backward along the guide slot and thereby fold the leg 78 to its retracted position shown in Fig. 5. Otherwise the bureau bed embodiment is substantially like the table bed. By this arrangement the rear legs 30 swing away from the drawers 68.

In the modified form of rear leg and folding means shown in Fig. 10, the leg 78', link 76' and shoulder 90' correspond with members 78, 76 and 90 respectively of Fig. 4, except that the guide slot is formed in the upper end of the leg and the shoulder is carried by the link. In this instance the curvature of the slot is of spiral shape so as to cause the coacting shoulder to gradually 40 and continuously approach or recede from the leg pivot 77 in turning section 16 upon section 18 and thereby swing the leg. Either of the leg folding arrangements shown in Figs. 4 and 10 may be used in 45 table beds if desired, as will be understood.

Although but two specific embodiments of this invention are herein shown, it is to be understood that no attempt has been made to show specifically all useful embodiments 50 and that numerous details of the constructions shown may be altered or omitted without departing from the spirit of this invention, as defined by the following claims.

We claim:

55 1. In a convertible bed a stationary frame in combination with a movable table top and a foldable bed bottom, said bed bottom being reciprocatable horizontally as a whole to and from its storage position and constructed to fold and unfold when withdrawn, and said top being supported by and hinged directly to said frame normally free of connection with said bed bottom, and leverage means pivoted to said frame, said 60 leverage means being operable by the for-

ward and backward movement of the bed bottom to raise and lower said table top respectively.

2. A convertible bed, comprising a stationary frame, in combination with a table top hinged thereto adjacent to their rear edges, a bed bottom reciprocatably mounted therein, a lever pivoted to the frame and having its arms formed and arranged for operatively connecting correspondingly formed portions of said top and bed bottom for simultaneous operation thereof one by the other for certain positions of the bed bottom, said lever being disengaged and inoperative for certain other positions of the bed bottom. 70 75 80

3. A convertible bed, comprising a stationary frame, in combination with a top hinged thereto and provided with a guide member disposed transversely of the hinged axis, a foldable bed bottom reciprocatably mounted for horizontal movement in said frame and having a pair of stop shoulders spaced apart longitudinally of the direction of movement thereof, and a lever pivoted to 90 the frame and having one end formed and adapted to coact slidably with said guide member and having its opposite end formed and adapted for coöperation with said shoulders. 95

4. A convertible bed, comprising a stationary frame, in combination with a reciprocatably mounted bed bottom carried thereby, a top member hinged to the frame independently of said bed bottom and a lever 100 connected for coacting with said frame and top and movable by the reciprocatory movement of the bed bottom, said lever being movable independently of said bed bottom when the latter is folded in place. 105

5. A foldable bed bottom, comprising a pair of sections hinged together, in combination with a pair of legs pivoted one behind the other on a side of one of said sections and a leg controlling link pivoted to the adjacent section and operatively connected to said legs for folding the same when said sections are folded and vice versa. 110

6. A foldable bed bottom, comprising an end section, a pair of legs pivoted to said section adjacent to its front and rear edges respectively, and a leg folding link pivoted at one end to the upwardly projecting end of the front leg and at its opposite end to a part of the next adjacent section spaced 120 somewhat from said end section, said link having a longitudinal slot and the upper end of the rear leg having a shoulder adapted to slide in said slot. 115

7. A convertible bed comprising a frame, 125 in combination with a top hinged directly to said frame and arranged to turn upward and backward when the device is to be used as a bed, a foldable bed bottom slidable as a whole horizontally into and out of storage 130

- 4.
- position in said frame, and mechanism mounted on the frame for actuating said top by the sliding movement of said bed bottom, said mechanism being arranged to permit the swinging of said top when said bed bottom is in storage position, and to permit the bed bottom to pass forward out of operative relation therewith in changing to bed form.
10. 8. A convertible bed, comprising a frame, in combination with a reciprocatably mounted foldable bed bottom having a panel member secured to one of the bed sections adapted and arranged to hold the side rails spaced apart and when said bed bottom is folded and retracted to conceal the same.
9. A convertible bed, comprising a frame, in combination with a hinged table top, a reciprocatably mounted foldable bed bottom having a panel member secured to one of the bed sections adapted and arranged to hold the side rails spaced apart and when said bed bottom is folded and retracted to conceal the same, connecting means arranged
- 20 for actuation by the bed bottom to swing the table top, said panel having a handle adapted to facilitate reciprocating the bed bottom.
10. In a device of the class described, a 30 slidably mounted foldable bed bottom comprising a series of alternate long and short
- sections adapted and arranged to lie horizontally and vertically respectively when folded, one of the short sections having a transverse panel member fastened to the 35 side rails, said panel member being spaced back from the plane of the section, and having drawer pull means.
11. A convertible bed, comprising a frame, a foldable bed bottom having roller 40 bearings for reciprocation forward and back in said frame, a table top hinged to the back of said frame at its upper edge, a lever pivoted at a medial point thereof to a side of said frame, said top having a guide way 45 adjacent to one side, one arm of said lever being secured to said guide way in sliding relation, adjustable friction means for slidably clamping said arm to said guide way, said bed bottom having a pair of shoulders 50 spaced apart on its side adjacent to said lever, and the opposite arm of said lever being disposed between said shoulders for movement thereby when the bed bottom is moved forward and back.

Signed at Chicago this 24th day of March, 1914.

JULIUS KRAMER.
DANIEL A. BRENNAN.
